FOREIGN PATENT DOCUMENTS

EP 2208957 A2 7/2010

Primary Examiner — Michael A Pratt

(74) Attorney, Agent, or Firm — Paul M. Thompson;
Cochran Freund & Young LLC**CLAIM**

The ornamental design for an ammunition magazine, as shown and described.

DESCRIPTION

FIG. 1 is an isometric view of an ammunition magazine showing our new design.

FIG. 2 is a right side elevation view thereof.

FIG. 3 is a left side elevation view thereof.

FIG. 4 is a rear elevation view thereof.

FIG. 5 is a front elevation view thereof.

FIG. 6 is a top plan view thereof; and,

FIG. 7 is a bottom plan view thereof.

The broken lines in FIGS. 1-7 are included for the purpose of illustrating use and environment and form no part of the claimed design.
